CLAIM

The ornamental design for a disposable diaper with integral disposal bag, as shown and described.

DESCRIPTION

FIG. 1 is a top plan view of a disposable diaper with integral disposal bag, showing my new design;

FIG. 2 is a bottom plan view thereof;

FIG. 3 is a right side elevation view thereof; the opposite side being a mirror image;

FIG. 4 is a front elevation view thereof; and,

FIG. 5 is a rear elevation view thereof.
